UNITED STATES PATENT OFFICE.

LORENZO H. SPARKS, OF TRIUMPH, OHIO.

WIND-ENGINE.

SPECIFICATION forming part of Letters Patent No. 246,427, dated August 30, 1881.

Application filed March 21, 1881. (Model.)

To all whom it may concern:

Be it known that I, LORENZO H. SPARKS, of 5
Triumph, in the county of Trumbull and State
of Ohio, have invented certain new and useful
Improvements in Wind-Engines; and I do hereby
declare that the following is a full, clear, 10
and exact description of the invention, which
will enable others skilled in the art to which
it appertains to make and use the same, refer-
ence being had to the accompanying drawings,
which form a part of this specification.

Figure 1 is a front view. Fig. 2 is a side
view. Fig. 3 is a top plan. Fig. 4 is a longi-
tudinal vertical sectional view.

15 Corresponding parts in the several figures
are denoted by like letters of reference.

This invention relates to wind-engines; and
it consists in certain improvements in the con-
struction of the same, which will be hereinafter
20 fully described, and particularly pointed out
in the claims.

In the drawings hereto annexed, A repre-
sents the standard or frame of the engine, which
is provided with a vertical tubular bearing, B,
25 for the frame C, which is provided with a sleeve,
D, by which it is mounted upon the said bear-
ing.

The body or sleeve D of frame C is provided
with a forward-projecting bracket, E, forming
30 a box or bearing for the main shaft F of the
wind-wheel G. The latter consists of a hub,
H, having inward-projecting brackets I, formed
with sockets for the radiating spokes K. Two
or more rims, L, are used, having diagonal slots
35 to accommodate the vanes N, which are firmly
wedged in the said diagonal slots. Mortises
are also provided in the rims L for the accom-
modation of the spokes K. The outer ends of
the brackets I of hub H are connected by braces
40 E with the outer rim L of the wheel, and simi-
lar braces connect the outside of said outer rim
with a disk, R, fixed upon the outer end of the
main shaft F, thus bracing and strengthening
the wheel.

45 H' H² are brackets projecting rearward from
the frame C and supporting a vertical pivotal
rod, U, to which a pair of brackets, V V, pro-
jecting in a forward direction, are firmly se-
cured. The upper bracket V is braced to the
50 forward-projecting bracket E by means of con-
necting-rods W, as shown. The brackets V V

are provided with bearings for the vertically-
sliding pump-rod X, the upper end of which is
curved in a forward and downward direction
over the upper bracket V, thus forming a U- 55
shaped bail, serving as a guide to steady the
motion of the upper end of the pump-rod. Be-
tween the end of the U-shaped guide and the
body of the pump-rod or pitman is pivoted a
connecting-rod, Y, connecting the said rod with 60
a crank-disk, Z, at the inner end of the main
shaft F, from which motion is thus communi-
cated.

A' is the vane, which is hinged by means of
straps B' upon the vertical rod U, upon which 65
it may turn in the direction indicated by the
arrow, it being prevented from turning in the
opposite direction by a cord or chain, C', by
which it is connected to a bracket, S, project-
ing laterally from the frame or turn-table C. A 70
rope or chain, J', secured to the same side of
the vane, is passed over a pulley, F', mounted
upon the bracket S, and over a vertical pulley
suitably mounted upon the turn-table. From
thence the said cord passes down through the 75
sleeve D to a point where it may be readily
reached and manipulated by a person standing
upon the ground, who is thus enabled to so ad-
just the vane as to throw the wheel out of the
wind in case of high wind or whenever it is de- 80
sired to slacken the motion. The opposite side
of the vane is provided with a bracket, H¹, hav-
ing an eye or bearing, I', for a rope or chain,
J², secured to this side of the vane and passed
over a pulley, K', mounted in a block, L', piv- 85
oted to a bracket, T, projecting laterally from
the frame or turn-table.

The end of rope J² is attached to an eye, N',
formed upon a rod, O', pivoted to the side of
the frame, and bent or curved as shown. The 90
rod O' is threaded, so as to receive an adjusta-
ble weight, P', by which the vane is thus coun-
terbalanced and held in its proper position,
while any sudden or jerking motion is obviated
when the wheel is in the act of turning to the 95
wind.

The bracket E of the frame C is provided
with a laterally-extending rod, Q', at right an-
gles to the axis of the wheel, and carrying at
its outer end a vane, R', adjusted just behind 100
the rim of the wheel. In the event of any sud-
den or strong gust of wind this vane will be

acted upon, thus turning the wheel partly out of the wind and preventing that sudden and jerking increase of speed which is so injurious to the machinery of ordinarily - constructed wind-engines.

From the foregoing description, taken in connection with the drawings hereto annexed, the operation and advantages of my invention will be readily understood. It is simple, inexpensive, durable in construction, and easily managed in case of high wind.

Having thus described my invention, I claim and desire to secure by Letters Patent of the United States—

15 1. The wheel G, formed of the hub H, having brackets I, the disk R, the radial spokes, the brace rods upon either side connecting with the outer ring L, and the vane-leaves N, se-

cured in the transverse slots in the duplex rings L, all combined and operating as set forth. 20

2. The tie C', to limit the action of the main vane in one direction, the bracket S, rope J', wheel G, and vane A', combined with the rope J², weighted lever O' P', and safety-vane Q' R', as and for the purposes set forth. 25

3. The looped pump-rod X, braces W, and pitman Y, combined with the piece V, crank Z, and shaft F, as and for the purposes set forth.

In testimony that I claim the foregoing as 30 my own I have hereto affixed my signature in presence of two witnesses.

LORENZO H. SPARKS.
